(57) **CLAIM**

The ornamental design for a base station for a cleaning robot, as shown and described.

DESCRIPTION

1.1 is a front view of a first embodiment of a base station for cleaning robot;

1.2 is a back view of the first embodiment;

1.3 is a left view of the first embodiment;

1.4 is a right view of the first embodiment;

1.5 is a top view of the first embodiment;

1.6 is a bottom view of the first embodiment;

1.7 is a perspective view of the first embodiment;

2.1 is a front perspective view of a second embodiment of base station for cleaning robot; and

2.2 is a back perspective view of the second embodiment.

(Continued)

In the reproductions, the broken lines depict portions of the base station for a cleaning robot that form no part of the claimed design.
